Specification of Letters Patent. Patented Aug. 18, 1914.

Application filed August 11, 1913. Serial No. 784,148.

To all whom it may concern:

Be it known that I, WILBUR E. SANDERS, citizen of the United States, residing at Sonora, in the county of Tuolumne and 5 State of California, have invented certain new and useful Improvements in Bins, of which the following is a full, clear, and exact description, reference being had to the accompanying drawings, forming a part 10 hereof.

My invention has relation to improvements in bins; and it consists in the novel features of construction more fully set forth in the specification and pointed out in the 15 claims.

In the drawings, Figure 1 represents a vertical cross-section of a conventional bin made according to my invention; and Fig. 2 is a vertical section on the zig-zag line 2—2 20 of Fig. 1.

The present invention is specially directed to improvements in bins designed for the storage, handling and delivery of fluent material such as ore in bulk, coal or other 25 mineral, rock, earth, sand, grain and other material whether crushed, granular, pulverized, or in any other condition, the object of the invention being to provide a bin (constructed of timber, metal, stone, concrete or 30 any other material, or combination of materials) of any available horizontal cross-section or contour, be the same square, oblong, circular, elliptical, or any other shape, and having any desired number of sections 35 or compartments, which shall combine in a single structure, the advantages of storage capacity, inherent in the horizontal or "flat-bottomed" bin, together with the fundamental advantages of the inclined-bottom bin (even when the latter is empty) of immediate delivery to the bin-chute for discharge, as the material is dumped into the bin from above in any of the ways known to the art.

45 A further object is to provide a bin which while combining the advantages aforesaid, yet eliminates the disadvantages which are inseparable from both the flat-bottomed and inclined bottom bins.

50 A further object is to construct a bin possessing strength, durability, stability, and other advantages better apparent from a detailed description of the invention which is as follows:—

55 Referring to the drawings, which repre-

sent a rectangular type of bin embodying my invention, and having a single compartment, 1 represents the bin having as shown, a horizontal or "flat-bottom" C—D adjacent to which is the discharge chute D—E—F—G provided with conventional gates K, K'. The material may be assumed to be dumped into the bin from a charge car O traveling on an overhead trestle T, or in any other way known to the art. The vertical cross-section of such a flat-bottomed bin (which cross-section is shown by the figure A—B—C—D—G—A) accommodates a maximum quantity or cross-section of material (a—o—C—D—G—p—a) the entire bin capacity being available for storage. The rectangular construction of bin referred to has the advantage too, that it is self-contained, all parts thereof being directly supported from the foundation or bed. Thus 65 type obviously is the simplest, strongest, and in all respects the most satisfactory, and per ton capacity, the most economically constructed, reinforced and repaired. In it the 70 repairs are reduced to a minimum in that the wear of parts by shock and abrasion is practically *nil*, since the material dumped into the bin falls upon, and must slide on similar material approximately along the inclined plane J—D, downward to the bin-chute D—E—F—G, for purposes of discharge. It affords a storage-room for the 75 material a space whose cross-section is represented by the triangle J—C—D, lying beneath and behind the inclined plane J—D, such space being absent in bins of the inclined-bottom type, and hence wasted. The 80 material thus stored in the space J—C—D beneath the plane J—D, which in the construction of the inclined-bottomed bin is the plane of the floor or bottom of such bin) is available for use and continued operation of the mill, in cases for example where the 85 mine or other source of ore supply is temporarily non-productive. On the other hand, the storing of the material in the space J—C—D has its disadvantages in that after 90 such material has been removed therefrom owing to a temporary suspension of the ore supply from the mine, an equal quantity 95 must be returned to said space and the surface of such material must be brought to the required slope-angle on which material dumped into the bin in the usual way will 100 run or slide down and deliver itself at the 105

chute D—E—F—G, for discharge. Therefore, other things being equal, until an amount of material equal to the cubic contents of the space J—C—D has been returned to the bin, no material will discharge from the bin-chute, the slope of the plane indicated by the line J—D approximating the slope of the angle of repose of the particular material being handled; and the material 10 can not run or slide toward the chute until this angle has been reached or slightly exceeded. The mill must of necessity therefore suspend operations until the requirements for the delivery of the material from 15 the bin are satisfied and the discharge thereof to the mill assured. Thus the advantage accruing from the storage of the material in the space J—C—D are counterbalanced by the disadvantages of suspension 20 of mill operations until an equal amount of material shall have been replaced within said space, and the delivery and discharge of the material at the bin-chute be re-established. The flat-bottomed bin is also unfavorable to the free delivery of material to the 25 bin-chute in cases where the material is wet or of a clayey consistence, such material refusing to run freely on similar material within the bin. In such a case the slope-angle or angle of repose (J—D—C) may increase almost to verticality, and in extreme cases the bin may become all but clogged.

With regard to the inclined-bottom bin, as for example that exhibited in vertical 30 cross-section by the figure A—B—J—D—G—A, wherein the floor or bottom of the bin is established approximately coincident with the inclined plane J—D, this construction affords immediate delivery at the chute, 35 of free material dumped into the bin in the usual way from above, as shown in approximate outline by the figure a—b—g—f—c—a. When however, the gates K, K', remain closed, the bin tends to fill up, the material 40 coning approximately as shown by the figure a—g—g—f—G—p—a, wherein, because of the bottom slope afforded by the inclined floor or plane J—D, the entire mass is available for immediate delivery at the chute 45 D—E—F—G. The conventional inclined-bottomed bin can be made sufficiently strong for all requirements, and yet, the pitch of the inclined floor thereof tends to render this type of bin less stable than is the more securely based flat-bottomed bin. Undoubtedly the inclined-bottomed bin is less securely foundationed than is the broader based flat bottomed bin, while the quantity of material it can accommodate is less than 50 that capable of being stored within the flat-bottomed structure, by an amount substantially equal to the contents of the space J—C—D. The shape of the inclined-bottomed bin being that of a wedge with its 55 edge downward, tends to cause the contained

material to wedge and pack itself into the lower part of the structure with the result that the front frames of timber bins are sometimes forced and sprung outward unless securely braced. The floor of the inclined-bottomed bin is subject to shock by reason of heavy material falling thereon, while the abrasive effect of sliding fragments tends rapidly to wear this part of the structure. 75

In the present embodiment of my invention I provide the flat-bottomed bin with an inclined false-bottom, leaf, or shelf, H—I supported in position in the bin in any suitable mechanical manner. The shelf may be 80 either an integral or permanent part of the bin structure, or it may be removable, either method being contemplated by my invention. In my improvement the shelf H—I occupies a position approximately coincident with the plane J—D, representing the plane of the inclined floor or bottom of an inclined-bottomed bin, the cross-section of which is represented by the figure A—B—J—D—G—A, the upper face of said shelf 90 presenting either a plane or otherwise fashioned surface. It may be stated in passing that the plane of the slope J—D may coincide with the inclination of the angle of repose of the material, or of even a steeper 95 angle, but the inclination should always be sufficient to cause a flow of the material toward the bin-chute. The lower edge of the false leaf or shelf H—I is lifted above the flat bottom of the bin to such a height as to 100 permit material lying stored behind said leaf to be shoveled from beneath the same to and into the bin-chute D—E—F—G, for discharge, whereby such stored material may be removed as desired and the bin emptied. 105 The upper edge I of this leaf extends upward to such a point as will make certain the deflection by the leaf of the falling material from above (a, a,—b, c), along the course b—c—f—g, and deliver the same to the 110 bin-chute for discharge. Thus deflected, the falling material will fill back beneath the lower edge II of the leaf, there forming (in section) the triangle d—e—g over the upper side d—g of which the flowing material will 115 slide to the bin-chute as clearly obvious from the drawing (Fig. 1). This means essentially immediate delivery at the chute for the discharging of material from the bin while it is empty. The form which this falling and flowing material will assume will approximate the figure a—b—d—c—g—f—c—a. If now the gates K, K', of the bin-chute are closed and the material continues to fall into the bin until it begins to overflow at the upper edge I of the shelf H—I, that which overflows will cone up upon the floor of the bin until finally the material will have assumed approximately the figure 120 a—h—k—l—m—n—b—d—e—g—f—G—j. 130

i-a. When however, the bin shall have been filled, the space *k-l-n-e-d-k* lying beneath and behind the leaf *H-I*, will have been filled from the overflow at *I* through the building up of the cone *l-m-n* until its surface *l-n* engages the bottom or under side of the leaf, and the material contained within the bin will correspond in cross-section approximately with the figure *a-o-C-D-G-p-a*, being the same cross-section as that of the material accommodated by a flat-bottomed bin and previously referred to. This entire mass of material contained within the bin, equally with the similar mass contained within the flat-bottomed bin as above noted, is available for delivery and storage, save and except the negligible quantity to be deducted because of the false-bottom or leaf *H-I*, and its supports (if any). The leaf *H-I* can readily be applied to any flat-bottomed or other bin already constructed, assuring immediate delivery of contained material at the bin-chute, and without in any wise affecting or lessening the storage capacity of the bin.

Because of the fact that as the bin fills the material will be forced by the superimposed mass into the space beneath and behind the leaf or shelf *H-I*, and for the same reason there packed to a degree whereby it of itself acts as a support for said leaf and the load resting thereon, it is evident that the leaf will not be called upon to support unassisted any extraordinary weight of overlying material, nor will extraordinary strength be required in its construction. Rather must the leaf be so established as to withstand successfully the impact of falling material and the abrasive action of sliding fragments upon its face. To perform this service the leaf or shelf need be relatively simple in construction, and may be readily strengthened, repaired and replaced.

45 The superposition of the leaf or shelf *H-I* over the bottom *C-D* of the bin, converts the latter into a combination flat-bottomed and inclined-bottomed bin, in which combination are present the advantages of each type of bin, with the disadvantages inherent in each type as commonly constructed, entirely eliminated. In other words, the presence of the leaf or shelf *H-I* insures the immediate delivery to the discharge-chute of material introduced thereto without affecting the storage capacity of the bin. By "flat-bottomed" as herein used is not necessarily meant a bin with a geometrically flat or plane horizontal bottom, but any equivalent bottom depressed below the plane defining the inclination or slope of the angle of repose for the material handled (as for example the plane *J-D*) and whereon the material will not run to discharge until it reaches such plane or slope.

The term "bin" is to be understood to mean any container whatsoever and is not to be considered as restricted specifically to what are generally termed "bins."

It will be seen by an examination of Fig. 1 that the outer side *d-g* of the triangle *d-e-g* forms in effect an extension of the upper face of the shelf *H-I*, which is itself disposed in the plane *J-D* defining the slope of the angle of repose of the fluent material; and since the bottom *D-E* of the discharge-chute is virtually coincident with the plane *J-D*, it follows that whether the bin be full or not, the material charged thereto will always be properly directed to the point of discharge along the inclined plane leading to said discharge point. If the bin is empty, the material falling on the shelf *H-I* will be directed by it immediately to the discharge-chute, or later as the triangle *d-e-g* builds up, the material will be directed over the face *d-g* of the triangle to the discharge-chute. By the term "triangle" of course, is meant the prism the cross-section of which is represented by the triangle referred to.

For convenience, the wall of the bin from which the discharge-chute leads may be regarded as the front wall, the opposite wall being the rear wall. The shelf *H-I* is thus spaced from both of said walls; it is spaced from the rear wall to allow the material to accumulate behind and under the shelf, and it is spaced from the front wall to leave sufficient opening between the flat-bottom and the front edge of the shelf for purposes of shoveling the material accumulated under the shelf, into the chute for discharge when occasion arises to draw on said material. The shelf too, by virtue of its position divides the bin into two intercommunicating compartments, one below the shelf and the other above the shelf, as clearly apparent from Fig. 1.

The disposition of the shelf *H-I* between the side walls of the bin and spaced from the front and rear walls as described, is not the only one contemplated by my invention; neither need the shelf be restricted to a member for which the term "shelf" or "leaf" is the most appropriate designation, it being understood that my invention contemplates broadly the interposition of any member, chute, or other device, in the path of the material charged into the bin from above, whereby said material so charged will be directed by said member to the discharge opening or chute for immediate delivery. In other words the invention contemplates the use of any device having an upper surface disposed at the proper slope to direct the material resting or impinging upon it, toward the discharge opening of the bin, it being understood that such device may be either permanent or removable, and

such as to allow material to store and pack behind it, and permit the material thus stored, to be shoveled from behind the device and the bin be thus emptied.

5. Having described my invention, what I claim is:—

In combination with a flat-bottomed bin having a bottom discharge opening and chargeable from a point above said opening, a shelf positioned in the bin above the

bottom thereof and spaced from said bottom and from the discharge opening, and operating to direct the material charged into the bin, toward said discharge opening.

In testimony whereof I affix my signature, 15 in presence of two witnesses.

WILBUR E. SANDERS.
